UNITED STATES PATENT OFFICE.

LEWIS ALEXANDER AND SAMUEL L. GANO, OF CLINTON, ILLINOIS.

RAILWAY-CROSSING.

No. 893,693.

Specification of Letters Patent.

Patented July 21, 1908.

Application filed February 29, 1908. Serial No. 418,614.

To all whom it may concern:

Be it known that we, LEWIS ALEXANDER and SAMUEL L. GANO, citizens of the United States, and residents of Clinton, in the county of DeWitt and State of Illinois, have invented certain new and useful Improvements in Railway-Crossings; of which the following is a specification.

This invention relates to railways, and 10 more especially to the crossings thereof; and the main object of the same is to produce a device of this kind applicable to cases in which the tracks cross each other at any angle, while the invention also contemplates 15 the production of a weather proof construction and one in which the rails of the track in use are automatically made continuous so as to lessen jar and noise and to avoid derailment.

20 To these ends the invention consists primarily in a base plate provided with a peculiar arrangement of slots, and rail-carrying tumblers journaled in four independent bearings adapted to be separately bolted to said plate according to the angle of the crossing; and it consists secondarily in the peculiar construction of the tumblers and their supports, and in the means for turning them—all as hereinafter more fully described and 30 claimed, and as shown in the drawings forming a part of this specification and in which—

Figure 1 is a general plan view of this crossing with certain parts at the different corners thereof removed or in section to 35 illustrate the construction of the parts beneath. Fig. 2 is a perspective view of one bearing with its tumbler withdrawn and slightly raised out of place. Fig. 3 is a bottom plan thereof. Fig. 4 is a detail of one 40 of the angular fish plates.

In the drawings the parts are broadly designated by reference letters as follows:

P designates the base plate, B the bearings, T the tumblers, O the operating mechanism therefor, and R the rails. The ties for supporting the latter and the base plate, and specific construction of the operating mechanism further than as necessary to an understanding of this invention, are not illustrated.

50 The base plate P is by preference a single rectangular sheet of metal, either solid or in skeleton form, supported on ties or otherwise as may be found desirable, and provided through its body at proper points with a series of transverse slots 1 and a series of oblique slots 2, either or both of which may

have right angular extensions as indicated as at 3; or in fact the entire plate, if of skeleton form, can be provided near its four corners with several series of slots so located and arranged as to permit the carrying out of the idea set forth below. While this plate is shown as flat (as that portion of it which forms part of the crossing will be), it is not inconsistent with or material to this invention that at other points on its surface, as near its edges, it could be provided with means for bolting or clamping it to the eight rails which constitute the crossing or to the ties.

The bearings B are duplicates of each other, and a description of one will suffice for all. Each comprises a preferably rectangular body 10 pierced near its corners with holes 11, and four bolts 12 which take through the slots in the base plate and whose nuts preferably stand at their upper ends so that they can be readily reached, and if desired may be held by nut locks forming no part of the invention. These 70 bodies are shown as superimposed upon the base plate, as they will be if the rails lie above its upper surface as in our preferred construction. By the use of transverse sets of slots 1 and oblique sets of slots 2 75 arranged in alternating series around the base plate, it is obvious that the bearings can be connected therewith at various points, nearer to or further from each other in pairs to accommodate narrow gage tracks 80 or standard gage tracks, and in right-angular or oblique angular position with respect to each other to accommodate right-angular crossings or those of acute or obtuse angles. The body of the bearing is preferably formed 85 with a raised annular boss 14 surrounding a central upright hole 15 through the bearing and having its upper end conical so that it slopes outward and will prevent water from passing through the hole; and an 90 opening 16 preferably parallel with one side edge of the body is cut through it and intersects one edge of the hole for reception of the rack bar which forms part of the operating mechanism. If the body rests flat on 95 the base plate, this opening is preferably made in the form of a groove in its lower face as seen in Fig. 3.

The tumbler T for each bearing has an upright cylindrical body 20 of a size to fit 100 closely but rotatably in the hole 15, a gear or pinion 21 opposite said opening 16 and

formed by cutting teeth in said body, and an enlarged head 22 formed with its under face slightly dished to fit the conical upper end of the boss 14 so as to shed water. Said head may also be provided with an annular flange 23 to receive a key to prevent its dislodgement, if desired. Superimposed upon and preferably cast with said head is a short rail section 25 which may be tempered if desired, this section being of a length to bridge the break in each of the rails forming parts of the tracks which cross each other. The rails R are of the usual construction, suitably supported on ties not shown, and also connected with and supported by the plate if desired, though not so illustrated herein. Their adjacent ends 30 preferably lie flat on the bodies 10 of the bearings and abut against the boss which by preference is a trifle larger in diameter than the head of its tumbler, and hence when the rails expand they may press against the boss but will not interfere with the rotation of the tumbler and its head. Adjacent rails are by preference connected on their outer sides by angular fish plates 31 whose angles are of such shape that when in place they engage the flanges 23 and form keys, and each checks the rotation of its adjacent tumbler when it has been turned so that the short rail section 25, thereon stands in line with either pair of adjacent rail sections 30. Said short section is of course made of sufficient length to allow clearance for the flange of the wheel when a train runs over the crossing. The operating mechanism O which forms a part of this invention comprises two parallel rods 40 extending through the openings 16 in the bearings and having teeth 41 at proper points to engage the pinions on the tumblers so that all of the latter will be turned simultaneously when the rods are moved in the proper direction. In Fig. 1 we have shown these rods as engaging the inner sides of two pairs of tumblers, and hence as connected by a link 42 so that they shall move oppositely and simultaneously. But it is obvious that if both rods lead to the right of all the tumblers the rods would have to move in unison to turn all the tumblers in unison. This would be satisfactory where the crossing is a right angular one and all tumblers must be turned through a quarter circle, but in the illustration where the crossing is an oblique one the tumblers are by preference turned through an arc bounded by the smallest angle at each point of crossing and the angular fish-plates are located in the arc bounded by the largest angle. As herein illustrated, the link 42 has an arm 43 connected as at 44 with the rod, that governs derailing at an interlocking plant. Movement of the arm will swing the link, and the latter will move the rods simultaneously and turn all the tumblers through

proper arcs to set their short rail sections in line with the rails of the track along which the locomotive is approaching. It is not considered necessary to illustrate how the opposite ends of the rods could be similarly operated, and it is quite within the province of our invention that another pair of rods and operating mechanisms could be arranged on the other track with similar results.

What is claimed as new is:

1. In a railway crossing, the combination with a substantially rectangular base plate having four series of slots in its body respectively near its corners; of a series of bearings mounted on the plate, bolts adjustably connecting them with the slots, tumblers journaled in said bearings and carrying short rail sections, means for turning the tumblers simultaneously, and the rails.

2. In a railway crossing, the combination with a base plate provided with slots in its body, said slots having right-angular extensions; of a series of bearings mounted on the plate, bolts adjustably connecting them with the slots, tumblers journaled in said bearings and carrying short rail sections, means for turning the tumblers simultaneously, and the rails.

3. In a railway crossing, the combination with a substantially rectangular base plate having four series of slots in its body respectively near its corners, those near diametrically opposite corners being transverse and the others oblique; of a series of bearings mounted on the plate, bolts adjustably connecting them with the slots, tumblers journaled in said bearings and carrying short rail sections, means for turning the tumblers, and the rails.

4. In a railway crossing, the combination with a substantially rectangular base plate having four series of slots in its body respectively near its corners, those near diametrically opposite corners being transverse and the others oblique, said slots having angular extensions; of a series of bearings mounted on the plate, bolts adjustably connecting them with the slots, tumblers journaled in said bearings and carrying short rail sections, means for turning the tumblers, and the rails.

5. In a railway crossing, the combination with a series of bearings, a tubular boss rising from each and having a conical upper end, a tumbler journaled in each boss and having a head dished on its under face and resting on said upper end of the boss, and a short rail section carried by said head; of the rails, means for holding them in place, and means for turning the tumblers.

6. In a railway crossing, the combination with a series of bearings, a tubular boss rising from each, a tumbler journaled in each boss and having a head resting on the upper end of the boss, the latter being of larger diameter than the head; of the rails whose ad-

jacent ends abut against said boss, means for holding them in place, and means for turning the tumblers.

7. In a railway crossing, the combination with a series of bearings, a tubular boss rising from each and having a conical upper end, a tumbler journaled in each boss and having a head dished on its under face and resting on said upper end of the boss, the latter being of larger diameter than the head, and a short rail section carried by said head; of the rails whose adjacent ends abut against said boss, means for holding them in place, and means for turning the tumblers simultaneously.

8. In a railway crossing, the combination with a series of bearings, a tubular boss rising from each, a tumbler journaled in each boss and having a head resting on the upper end of the boss, the latter being of larger diameter than the head, and a short rail section carried by said head; of the rails whose adjacent ends abut against said boss, means for holding them in place, angular fish plates connecting contiguous rails and passing around said boss through the path not occupied by said rail section in its movement, and means for turning the tumblers.

9. In a railway crossing, the combination with a series of bearings, a tubular boss rising from each, a tumbler journaled in each boss and having a head resting on the upper end of the boss, and a short rail section carried by said head; of the rails, means for holding them in place, angular fish plates connecting contiguous rails through the path not occupied by said rail section in its movement, and means for turning the tumblers simultaneously so that their rail sections shall move through a path not occupied by said fish plates.

10. In a railway crossing, the combination with a series of four upright bearings provided with two parallel openings intersecting the edges of the holes through the bearings, tracks whose rails have breaks over said holes, tumblers journaled in the latter and carrying short rail sections adapted to bridge the breaks, and pinions on the tumblers whose teeth project into said openings; of rods mounted in the latter and having teeth engaging the pinions, a link connecting the

rods, and means for moving the link to reciprocate said rods simultaneously.

11. In a railway crossing, the combination with a series of four upright bearings provided with two parallel openings intersecting the adjacent edges of the holes through all of them, tracks whose rails have breaks over said holes, tumblers journaled in the latter and carrying short rail sections adapted to bridge the breaks, and pinions on the tumblers whose teeth project into said openings; of rods moving in the latter and having teeth engaging the pinions, a link connecting the rods, and means for moving the link to reciprocate said rods simultaneously and in opposite directions.

12. A bearing for railway crossings comprising a body, a tubular boss rising therefrom, a tumbler journaled therein, a head on the tumbler resting on the boss, and a short rail section on the head; combined with the adjacent rails, and means for rotating the tumbler from a remote point.

13. A bearing for railway crossings comprising a body having a transverse opening, a tubular boss rising therefrom and whose hole is intersected by said opening, a tumbler journaled therein, a head on the tumbler resting on the boss, and a short rail section on the head; combined with the adjacent rails, and means for rotating the tumbler, the same comprising a pinion attached to it and projecting into said opening, a rack bar movable in the latter and engaging the pinion, and means for moving said rack bar.

14. A bearing for railway crossings comprising a body, a tubular boss rising therefrom, a tumbler journaled therein and having an annular flange forming a key-way, a head on the tumbler resting on the boss, and a short rail section on the head; combined with the adjacent rails, an angular fish-plate connecting them and engaging said key way, and means for rotating the tumbler.

In testimony whereof we sign our names in the presence of two subscribing witnesses, this the 17th day of February, 1908.
